UNITED STATES PATENT OFFICE.

SAMUEL W. STATTON, OF MINNEOLA, KANSAS.

OIL-BURNER.

1,030,211.

Specification of Letters Patent. Patented June 18, 1912.

Application filed May 12, 1911. Serial No. 626,682.

To all whom it may concern:

Be it known that I, SAMUEL W. STATTON, a citizen of the United States, residing at Minneola, in the county of Clark and State 5 of Kansas, have invented new and useful Improvements in Oil-Burners, of which the following is a specification.

This invention relates to oil burners for stoves or furnaces, the object of the invention being to provide a simple and effective 10 construction of burner which may be formed mainly of tubing or piping, whereby economy of manufacture is secured.

The invention consists of the features of 15 construction, combination and arrangement of parts, hereinafter fully described and claimed, reference being had to the accompanying drawing, in which:—

Figure 1 is a side elevation of an oil 20 burner embodying my invention. Fig. 2 is a top plan view thereof. Fig. 3 is a vertical transverse section. Fig. 4 is a longitudinal section through one of the burner tubes. Fig. 5 is a vertical transverse section thereof. Fig. 6 is a view of a cleaner employed 25 in connection with the invention.

The burner comprises a pair of parallel 30 burner pipes or tubes 1 and 2 disposed in the same horizontal plane and connected at one end by a return bend or U-shaped coupling comprising elbows 3 and a T-joint or coupling member 4. An oil supply pipe 5 extends above and on a line centrally between the burner pipes and is connected at its inner 35 end with the return bend by an elbow, whereby oil and gas from said pipe will be equally distributed to the burner pipes. The portion of the oil supply pipe lying immediately above the burner pipes forms a 40 generator, lying within the zone of the flames and heat from the burner pipes, whereby the oil passing therethrough is converted into vapor in the operation of the burner and thence flows to the burner pipes 45 for consumption.

Each burner pipe is closed at its outer end, or end opposite its point of connection with the return bend, by a screw plug 6 and is provided in its sides with rows of 50 jet orifices 7 for the outflow of oil or gas, which is ignited on the outer side of the pipe. Each of said pipes is also provided in its upper side with one or more jet orifices 8 at which the issuing gas is ignited 55 to supply flames to play against the superposed generator portion of the oil supply

pipe, for heating the latter effectually for the conversion of the oil into vapor. These openings 8 are conveniently formed by boring a hole 9 in the bottom of the pipe and 60 in the same operation partially boring through the top wall of the pipe to form a recess 10, thus reducing the surface of the pipe to a thin web, as at 11, in which the opening 8 may be conveniently punched. 65 The wall of the opening 9 is threaded to receive a plug 12, whereby it is closed in the operation of the apparatus. This method of forming the openings 8 not only allows them to be made of any convenient size and to be 70 punched instead of drilled, but also provides the opening 9 through which a tool or implement may be introduced to clean the opening 8 and facilitate cleaning of the interior of the burner pipe, into which a 75 cleaning implement may also be introduced upon the removal of the plug 6.

The formation of the openings 8 and webs 11 provides enlarged recesses in the top walls of the burner pipes which communicate with said openings 8, and through which the vapor flows on its passage to said openings. These recesses thus serve to collect and retain the solid particles flowing out with the vapor, thus diminishing the 85 liability of the choking of the jet openings from the deposit of soot and other impurities.

Arranged below the burner pipes is a starting pan 13 adapted to hold an initial 90 supply of oil which is ignited to supply heat for starting the apparatus into operation at the outside. This pan is provided with inwardly extending supporting arms 14 having hooks or loops 15 to embrace the 95 burner pipes, whereby it may be slidably applied and removed from the free ends of the burner pipes.

In starting the apparatus into operation, a small quantity of oil may first be placed 100 in the burner pan and ignited to heat the burner pipes and supply pipe to start the generation of gas, or the controlling valve 16 in the supply pipe may be opened to allow oil to flow to the burner tubes and through the jet orifices therein to the pan, such supply of oil being ignited for the purpose described. After the generator portion of the pipe 5 is sufficiently heated, the oil is converted into vapor therein and flows 105 to the burner pipes and out through the jet orifices therein, at which points it is 110 ignited.

nited. These flames and particularly the flames from the orifices 8 play against the generator portion of the oil supply pipe and thus keep it at all times heated for the effective generation of gas. In connection with the apparatus, a cleaning tool 17 of the type shown in Fig. 6 may be employed. This consists of a flat blade or strip carrying a handle 18 at one end and having a right angularly bent free end 19 formed with a segmental recess 20 adapted to partially encircle either burner pipe. Said portion 19 forms a rake or scraper by which, on the reciprocation of the pull along the pipe, any accumulated deposits of carbon may be removed.

Having thus described the invention, I claim:

An oil burner comprising a pair of par-

allel burner pipes, connected at one end by 20 a return bend and each closed at its opposite end, said pipes being provided with rows of lateral orifices and top orifices, the latter communicating with enlarged retaining recesses in the top wall of the pipe, each 25 burner pipe having an opening in its bottom in line with each top orifice and recess, a closure for said opening, and an oil supply pipe extending above and centrally between the burner pipes and connected at one 30 end with the return portion.

In testimony whereof I affix my signature in presence of two witnesses.

SAMUEL W. STATTON.
